A. E. HEADLEY

SHOE PRESSING MACHINE

Filed April 14, 1925

Fig. 2.

INVENTOR

Arthur E. Headley
by his Attorney
Kelson & Headley

UNITED STATES PATENT OFFICE.

ARTHUR EDWARD HEADLEY, OF LEICESTER, ENGLAND, ASSIGNOR TO UNITED SHOE MACHINERY CORPORATION, OF PATERSON, NEW JERSEY, A CORPORATION OF NEW JERSEY.

SHOE-PRESSING MACHINE.

Application filed April 14, 1925. Serial No. 23,040, and in Great Britain April 22, 1924.

This invention relates to shoe pressing machines and is disclosed as embodied in a leveling machine of the so-called direct pressure type such as is shown, for example, in United States Letters Patent No. 1,359,507, granted on November 23, 1920, upon an application of Arthur E. Jerram and Joseph Gouldbourn. It may be stated here that since the present problem is essentially a last supporting problem, reference will be made herein-after particularly to the last, but it will be understood that the supported last has a shoe on it and that the supporting means may, as herein illustrated, support the last through contact with the shoe upper on it.

Shoes have been leveled, in the past, in several ways. Welt shoes have been leveled on wooden lasts in rolling pressure machines of several types; while McKay shoes, prior to the inventions described in Letters Patent No. 1,563,576, granted on December 1, 1925, upon an application of F. B. Keall and W. T. Minett, and No. 1,615,869, granted on February 1, 1927, upon an application of B. P. Cooper, have been leveled on iron lasts in so-called direct pressure machines. The inventions claimed in the last-mentioned patents have enabled both welt shoes and McKay shoes to be leveled on their wooden lasts by the use of direct pressure machines through the provision of a so-called cradle support, thus providing distinct improvements in the leveling of welt shoes and at the same time providing for better leveling of McKay shoes as well as avoiding the necessity of having separate machine equipment for leveling welt or McKay shoes.

When the wooden lasts are of the movable heel part type, or more specifically of the hinge type, difficulty may arise with both types of leveling machines in that the bonding mechanism between the heel and fore parts of the last may be too weak to take the pressure of the leveling tool, so that the last is distorted or broken and the shoe on it is in either event damaged.

It is a principal object of the present invention to prevent such damage, and to this end a feature of the invention consists in an improved shoe-pressing or leveling machine organization in which a shoe and its last are

supported for the pressing or leveling operation by means comprising an intermediate support for the last located, in the construction shown, in the neighborhood of the joint between the heel end and the forepart. Preferably this support will be in addition to the heel and forepart (or toe) supporting mechanisms characteristic of leveling machines of the types discussed above. In the embodiment shown, the supporting mechanism comprises separate members in angular relation to each other for supporting the lateral faces of the last on both sides through contact, as herein illustrated, with a shoe upper on the last.

Another feature of the invention consists in a novel organization including provision for adjustment of the supporting means to conform to different shapes or sizes of lasts. In the disclosed machine there is provision for adjustments which permit desired changes in the distance between the shoe engaging members, a pivotal mounting construction which enables these members to be angularly placed in the best position to support the particular last in the machine, and also provision for adjusting the intermediate supporting means as a whole laterally and longitudinally of the last.

These and other features of the invention comprising certain novel combinations and arrangements of parts will be understood from the following description of a preferred embodiment thereof selected for purposes of illustration and shown in the accompanying drawings, in which,

Fig. 1 illustrates in side elevation those parts of a leveling machine of the direct pressure type which are essential to an understanding of the invention, and

Fig. 2 is an end elevation, partly in cross-section on the line 2—2 (Fig. 1), of the same parts.

As already stated, the illustrated machine is of the type shown in the Jerram and Gouldbourn patent referred to, to which reference may be had for more detailed description of the construction, arrangement and operation of parts not fully described herein. The power-operated leveling form 52 is shown herein only diagrammatically. Its

construction and operation on the shoe will be understood from the patents mentioned. For purposes of this invention a bracket 1 is slidingly mounted between forepart and heel end supports 2 and 3 on a dove-tailed way 4 which also carries the heel end support. The forepart support 2 carries a forepart cradle member 2* formed substantially to fit the forepart of a last from the toe to the instep and is adjustable along a dove-tailed way 2** to accommodate different lengths of shoes similarly to the heel end support 3, as described in the Cooper patent above referred to. The shoe B on its last C is shown supported on these supports as described in said patent. The bracket 1 is mounted independently upon the way 4 and may be adjusted along the way lengthwise of the shoe according to the size of the latter without regard to the position of the heel end support 3 or that of the forepart support 2. The bracket 1 has an upwardly extending arm 5 at each side of the shoe. The arms 5 support shoe engaging members 7, which are preferably faced with felt or other material as shown, to prevent damage to the shoe when the last is pressed between them. The members 7 are inclined upwardly away from each other so as to form a V-shaped opening to receive that portion of the last where the last hinge is located, in correspondence with which they may be longitudinally positioned by means of the sliding relation of the bracket 1 to the way 4.

Each of the arms 5 is threaded for two transverse screws 9 and 10. The screws 9 extend upwardly and inwardly through the arms 5 and contact at their inner ends with the central portions of the members 7. The screws 10 extend horizontally through the arms 5 and have short reduced portions at their inner ends extending through considerably larger holes in the lower ends of the members 7, which are prevented from losing contact with the screws by pins 11.

Thus an adjustment of all the four screws in the same general direction will move both the engaging members 7 bodily in the same direction laterally of the shoe: by moving the screws on the left and the right (Fig. 2) in opposite directions the members 7 can be brought closer together or farther apart: and by moving the screws 9 and 10 of the same side in opposite directions or by moving either screw alone the corresponding member 7 can be tilted laterally of the shoe. If, for example, the screw 10 connected to the lower end of the member 7 is adjusted, the member 7 will be tipped about an axis extending lengthwise of the shoe through its point of contact with the screw 9; while if the screw 9 is adjusted, the member will be tipped about a similar axis located at its connection with the screw 10. It will be readily understood that an adjustment of the members 7 toward

or away from each other will enable them to reach the last properly whatever its elevation above the way 4 may be, due to its support on the forepart and heel end supports 2 and 3. The members 7 are provided with flanges 12 and 13 which extend like the arms of a U about the arms 5 and the screw-ends 9. As these members rest on the ends of the screws 9 they are thus enabled to turn about axes extending heightwise of the shoe (in view also of the nature of their support on the inner ends of the screws 11) to adjust themselves to the contour of the last. The intermediate last supporting mechanism is thus adjustable as a whole lengthwise and laterally of a shoe supported by the supports 2 and 3, and its members 7, in addition to being bodily movable toward or from each other, have, in effect, a universal joint adjustment about the ends of the screws 9 as well as an adjustment about the ends of the screws 10.

A metal band 50, preferably felt lined, is secured to the base of the heel end support 3 and extends around the heel end of the shoe upper to prevent rearward displacement of the shoe during the leveling operation, as disclosed in the Cooper patent referred to.

Having thus described my invention, what I claim as new and desire to secure by Letters Patent of the United States is:

1. In a shoe pressing machine, a pressing member, means for supporting a last and shoe at its forepart and at its heel end, and means for engaging the shoe between its heel and fore parts to support it under the pressure of the pressing member, said last-named means comprising shoe-engaging members movable relatively to each other to fit the contour of the engaged portion of the shoe.

2. In a shoe pressing machine, a pressing member, a last heel support, a last forepart support, and means for supporting the last additionally between these two supports, said additional supporting means comprising members spaced apart for engaging only the side faces of the shoe.

3. In a shoe pressing machine, a pressing member, a last heel support, a last forepart support, and additional means for supporting a jointed last between said supports substantially at the joint between its heel and fore parts.

4. In a shoe pressing machine, a pressing member, a last heel support, a last forepart support, and additional means for supporting a jointed last between said supports substantially at the joint between its heel and fore parts, said additional means being adjustable longitudinally of the last.

5. In a shoe pressing machine, a pressing means, a last heel support, a last forepart support, and additional means for supporting a jointed last between said supports substantially at the joint between its heel and fore parts, said additional means being ad-

- justable independently of either of said supports and of any adjustment thereof.
6. A leveling machine having leveling means, and a support for a hinge last for a leveling operation on the tread face of the sole of a shoe mounted thereon, comprising a forepart support, a heel end support and additional supporting means between these two arranged to support the last in a location substantially under the hinge. 70
7. In a shoe sole leveling machine, pressing means, and means for supporting a jointed last for the presentation of a shoe thereon to the pressing means comprising a last heel support, a last forepart support, and additional means for supporting the last between said supports substantially at the joint between its heel and fore parts, said additional means being adjustable laterally of the last. 75
8. In a shoe pressing machine, a pressing tool, a last heel support, a last forepart support, and additional means for supporting a jointed last between said supports substantially at the joint between its heel and fore parts, said additional means being adjustable to effect operative contact with a shoe on the last irrespective of its vertical position on said supports. 80
9. In a shoe pressing machine, a power-operated pressing means, a last heel support, a last forepart support, and additional means for supporting the last between said supports, said additional means having a plurality of shoe engaging portions relatively movable to conform to the contour of the last being supported, irrespective of size or style. 85
10. In a shoe pressing machine, a power-operated pressing means, a last heel support, a last forepart support, and additional means for supporting the last between said supports, said additional means having a plurality of shoe engaging portions which are rotatable relatively to each other to conform to the contour of the last being supported, irrespective of size or style. 90
11. In a shoe pressing machine, a pressing form, a last heel support, a last forepart support, and additional means for supporting the last between said supports, said additional means having a plurality of shoe engaging portions which are rotatable each about an axis extending longitudinally of the last to conform to the contour of the last being supported, irrespective of size or style. 95
12. In a shoe pressing machine, a pressing member, a last heel support, a last forepart support, and additional means for supporting the last between said supports, said additional means having a plurality of shoe engaging portions which are rotatable each independently about an axis extending heightwise of the last to conform to the contour of the last being supported, irrespective of size or style. 100
13. In a shoe leveling machine, a leveling means, a last heel support, a cradle substantially fitting the last forepart from the toe to the instep, and an auxiliary last supporting means arranged to support the last between the heel support and the cradle. 105
14. In a shoe pressing machine, a pressing member, a last heel support, a last forepart support, and additional means for supporting a hinge last between said supports in a location substantially under the hinge between its heel and fore parts, said additional means comprising an arm and a last supporting member pivotally mounted on the arm. 110
15. In a shoe pressing machine, a pressing tool, a last heel support, a last forepart support, and additional means for supporting the last between said supports, said additional means comprising an arm and a last supporting member pivotally mounted on the arm for movement about an axis extending heightwise of the shoe. 115
16. In a shoe pressing machine, a pressing tool, a last heel support, a last forepart support, and additional means for supporting the last between said supports, said additional means comprising an arm and a last supporting member mounted on the arm and universally movable about a point of its support on the arm. 120
17. A direct pressure leveling machine comprising a form-shaped leveling member, a cradle forepart support having substantially the contour of the last forepart upon which a shoe is to be leveled, a last heel support, and additional means for supporting a jointed last between the cradle and the heel end support substantially at the joint between its heel and fore parts against the pressure of the leveling member. 125
18. A direct pressure leveling machine comprising a form-shaped leveling member, a cradle forepart support having substantially the contour of the last forepart upon which a shoe is to be leveled, a last heel support, and additional means for supporting the last between the cradle and the heel end support against the pressure of the leveling member, said additional means being adjustable laterally of the last. 130
19. A direct pressure leveling machine comprising a form-shaped leveling member, a cradle forepart support having substantially the contour of the last forepart upon which a shoe is to be leveled, a last heel support, additional means for supporting the last between the cradle and the heel end support against the pressure of the leveling member, and a support for said additional means comprising a guideway on which said means is mounted for rectilinear sliding movement to adjust it longitudinally of the last relatively to the cradle and the heel end support. 135
20. In a shoe-pressing machine, the combination with means for applying pressure to 140

the bottom of a shoe on a last, of a support for the forepart of the last, a support for the heel end of the last, and additional means for supporting the last between said forepart and heel end supports comprising members arranged to provide a substantially V-shaped opening between them to receive the last, said members being relatively adjustable bodily to vary the distance between them.

10 21. In a shoe-pressing machine, the combination with means for applying pressure to the bottom of a shoe on a last, of a support for the forepart of the last, a support for the heel end of the last, and additional means for supporting the last between said forepart and heel end supports comprising members arranged to provide a substantially V-shaped opening between them to receive the last, said members being relatively movable to vary their angular relation to each other.

22. In a shoe-pressing machine, the combination with means for applying pressure to the bottom of a shoe on a last, of a support for the forepart of the last, a support for the heel end of the last, and additional means for supporting the last between said forepart and heel end supports comprising members arranged to engage respectively the opposite sides of the shoe, said members being movable both in the same direction laterally of the shoe and also relatively movable laterally of the shoe to conform to different shoes.

23. In a shoe-pressing machine, the combination with means for applying pressure to the bottom of a shoe on a last, of a support for the forepart of the last, a support for the heel end of the last, additional means for supporting the last between said forepart and heel end supports comprising members arranged to engage respectively the opposite sides of the shoe, and means associated with each of said members for adjusting it independently of the other in directions laterally of the shoe.

45 24. In a shoe-pressing machine, the combination with means for applying pressure to the bottom of a shoe on a last, of a support for the forepart of the last, a support for the heel end of the last, and additional means for supporting the last between said forepart and heel end supports comprising members arranged to engage respectively the opposite

sides of the shoe, each of said members being independently adjustable about either of two axes extending lengthwise of the shoe at different distances from the bottom of the shoe.

55 25. In a shoe-pressing machine, the combination with means for applying pressure to the bottom of a shoe on a last, of a support for the forepart of the last, a support for the heel end of the last, additional means for supporting the last between said forepart and heel end supports comprising members arranged to engage respectively the opposite sides of the shoe, adjusting means connected to said members at one end of the latter for swinging them each about an axis between its ends and extending lengthwise of the shoe, and additional means for swinging said members about their connections to said adjusting means.

60 26. In a shoe-pressing machine, the combination with means for applying pressure to the bottom of a shoe on a last, of a support for the forepart of the last, a support for the heel end of the last, additional means for supporting the last between said forepart and heel end supports comprising members arranged to provide a substantially V-shaped opening between them to receive the shoe, said members being swiveled to permit them to adjust themselves each independently to the contour of the shoe about an axis extending heightwise of the shoe, and means for adjustably tipping each of said members independently of the other laterally of the shoe.

65 27. In a shoe-pressing machine, the combination with means for applying pressure to the bottom of a shoe on a last, of a support for the forepart of the last, a support for the heel end of the last, additional means for supporting the last between said forepart and heel end supports comprising members arranged to engage respectively the opposite sides of the shoe, said members being swiveled to permit them to adjust themselves each independently to the contour of the shoe about an axis extending heightwise of the shoe, and means for effecting an additional adjustment of each member about either of two axes extending lengthwise of the shoe.

70 In testimony whereof I have signed my name to this specification.

ARTHUR EDWARD HEADLEY.
